SIDEWALK DOOR

John William Lovatt, Paterson, N. J.

Application April 19, 1934, Serial No. 721,377

7 Claims. (Cl. 94—36)

This invention relates to doors and what may be termed a sidewalk door, the object being to provide a construction which may be used in sidewalks and other places and present a construction which will have a number of advantages including being substantially waterproof.

Another object of the present invention is to provide a door for sidewalks, hatchways, manholes, vaults or in any interior or exterior opening, horizontal, perpendicular or sloping, and presenting a substantially safe, non-slipping flush-type structure which is reasonably air and waterproof as well as noiseless and sanitary.

A further object of the invention is to provide a door for sidewalks and the like wherein all the parts of the door are flush with the sidewalk or other surface on which the door is mounted, and at the same time in which means are provided for reinforcing and supporting the door so as to resist pedestrian traffic or even heavier traffic.

A still further object of the invention is to provide a sidewalk door or the like with a specially formed hinge which will be flush with the remaining part of the door when the door is closed, and when open will act as means for properly supporting the door at an angle to the vertical.

An additional object of the present invention is to provide a sidewalk door or the like with a locking structure and a key which will act as a handle for the door and function to maintain the door unlocked as long as the handle is in use, and to cause the door to be locked when the handle is removed.

In the accompanying drawings—

Figure 1 is a top plan view of a sidewalk door disclosing an embodiment of the invention;

Figure 2 is a sectional view through Figure 1 approximately on the line 2—2;

Figure 3 is a top plan view of the door with certain parts broken away and one of the hinges shown in Figure 1;

Figure 4 is an edge view of the structure shown in Figure 3;

Figure 5 is a sectional view through Figure 3, the same being taken on the line 5—5;

Figure 6 is a sectional view through Figure 3 on the line 6—6;

Figure 7 is a fragmentary view of one of the door members with a gasket disclosing certain features of the invention;

Figure 8 is a fragmentary sectional view through Figure 1 on the line 8—8, the same being on a greatly enlarged scale;

Figure 9 is a sectional view through Figure 8 on the line 9—9;

Figure 10 is a top plan view of the structure shown in Figure 9;

Figure 11 is a perspective view of the core member used in the lock illustrated in Figures 8 and 9;

Figure 12 is a perspective view of the plug used in the lock shown in Figure 8;

Figure 13 is an enlarged fragmentary sectional view through Figure 1 on the line 13—13;

Figure 14 is a side view of the entire door as shown in Figure 1 before the concrete has been cast around the same, the view illustrating how leveling screws are used to properly position the door frame before the concrete or other filling is used.

In the accompanying drawings an embodiment of the invention is disclosed, which is shown as a sidewalk door arranged in a sidewalk formed of concrete or similar material. The invention may be applied specifically as shown in the drawings, or may be embodied in manhole covers, vault doors, or other constructions without departing from the spirit of the invention, and the expression "sidewalk door" is intended to cover all of these and any other uses to which the invention might be applied.

As shown in the accompanying drawings, the sidewalk is indicated by the numeral 1 and is provided with a hole or opening 2 entering into the sidewalk, cellar or other compartment. Embedded in part of the sidewalk and surrounding the opening 2 is a frame 3 formed of angle iron with a vertical leg arranged parallel to the side walls of the opening 2 though, if desired, it could overhang this opening or even be set back therefrom. The other leg forms a horizontal supporting structure on which suitable supporting bars 4 are mounted and secured in place by any means as, for instance, rivets or screws 5 (Fig. 9). These bars are offset as indicated at 6 so that when concrete is applied it will not be in contact with the cover plates 7 forming part of the doors 8 and 9. The bars 4 extend entirely around the opening 2 on the horizontal leg of the frame except at the hinge portions, and present a supporting structure for taking up the weight of the door which is transmitted from the respective cover plates 7.

The same general arrangement is made at the center, namely, a transverse supporting bar 4' is riveted to the cover plate 7 of door 9, and to this bar is riveted an inverted supporting channel iron 10. The channel iron 10 has the upper surface flush with the upper surface of the frame 3.

and the lower edges positioned to rest on the bars or lugs 11 welded to the frame at each end thereof. It will be noted that the lugs 11 are arranged at the ends of the frame, while the respective 5 hinges 12, 13, 14, and 15 are at the sides. By providing the supporting bars 4 and 4' all the weight is transmitted through these bars to the frame 3, and from the frame 3 to the concrete of the pavement as the concrete is poured in so as to fit 10 beneath this frame in order that the frame may be carried thereby. In order that the frame 3 may be properly leveled before the concrete is poured, or during the setting of the frame, short sections of channel iron 16 are welded to the 15 frame 3 near each corner of the frame, and through each of these short sections extend adjusting bolts 17 which engage a suitable surface therebelow as shown in Figs. 2 and 14, whereby the frame may be properly leveled. After the 20 frame has been properly leveled the concrete is poured and acts as a support for the frame and also acts to hold the frame in proper position as it is substantially embedded in the concrete. After the frame has been properly set the doors 25 8 and 9 are applied. It will be noted that the doors 8 and 9 are preferably removed before the frame is set and reapplied afterwards. This allows the workmen to have access to both the inside and the outside of the frame during the 30 setting thereof.

Arranged alongside of the supporting bars 4 are gaskets 18, and arranged alongside of the supporting bar 4' are gaskets 18' and 18''. All of 35 these gaskets are identical in construction and are formed as shown in Fig. 7.

As illustrated in Fig. 7 the gasket 18 is formed with a rubber body 19 having a concave upper surface 20, a recessed portion 21 and downwardly projecting parallel ribs 22 and 23. In addition, the metal plate 24 is fitted into the depression 21 and extends for the full length of the depression. This plate is provided at suitable intervals with threaded apertures for receiving the respective screws 25, which screws extend through the cover plate of the respective doors. In Fig. 5 the gasket is shown as applied to a door when in its final functioning position. The screw 25 is operated until the bar 24 is pulled upwardly sufficiently to cause the concave part 20 to fit flatwise against the cover plate, as illustrated particularly in Figs. 40 8 and 9. This causes the edge portions 26 and 27 to fit tightly against the cover plate and, in addition, causes the ribs 22 and 23 to incline slightly inwardly. These ribs when the screw has 45 been completely tightened extend normally slightly below the supporting plates 4, so that when the doors 8 and 9 are closed these ribs will be somewhat compressed and thereby present a watertight and even airtight seal. However, the weight of the door and the weight of any object 50 placed thereon is not carried by the gasket but is carried by the respective supporting bars 4 and 4'. It will be noted that these gaskets are arranged interiorly of the bar 4 and are consequently 55 protected from the elements to a large extent by these bars. It will be understood that the frame 3, bars 4, cover plates 7 and associated parts are formed from steel of any desired grade, for instance, ordinary open hearth steel. Also, these 60 members are made from commercial stock and consequently may be cut readily to fit any size of opening so that any sized door may be readily applied without forming new patterns or securing new castings.

70 In forming the hinges there are provided cer-

tain sockets and other members which may be forged or, if desired, may be cast because they are always of the same size and may be used either with a large or a small door. All the 5 hinges 12 to 15, inclusive, are identical in construction and therefore a description of hinge 15 will apply to all of the hinges. In forming the hinge there is provided either a forging or a casting 10 28 which is formed with what may be termed a socket 29 having a thickened portion 30, a flange 31 and a bracing web 32, said flange being bolted or otherwise rigidly secured to the frame 2. The socket 29, as shown in Figs. 4 and 5, is provided with a chamber 33 and with portions 34 and 35 which extend above the frame 3 so as to receive the 15 respective hinge blocks 36 and 37. The hinge blocks are each provided with openings 38 for receiving a pintle 39, and also with an extension 40 for receiving the respective screws 41, which screws extend through the extensions and also 20 through the frame 3 so as to readily clamp the hinge blocks in place. It will be noted that each of the hinge blocks is provided with a depression or notch 42 so formed as to receive the edge 25 of a cover plate 1 whereby the top of the cover plate is flush with the top of the upper part of the hinge block. It will be noted further that these two hinge blocks are held in place by screws which are covered by the cover plate when the doors are closed. Arranged between the blocks 30 36 and 37 is a hinge block or knuckle 43 which is provided with an extension 44 secured to the cover plate 1 by a suitable screw 45 whereby the knuckle 43 and the cover plate will swing together around the pintle 39 which is supported by the 35 blocks 36 and 37. The knuckle 43 is provided with a straight shoulder 46 adapted to fit flatwise against the shoulder 47 of the thickened portion 30 when the door is closed. In addition, there is a hook 48 adapted to rest against the outer 40 under surface 49 of frame 3, as shown in dotted lines in Fig. 2 when the door is open. Part of the upper surface of the block 43 will rest against the thickened portion 30 and hook 48 will engage the surface 49 when the door is fully opened, thus 45 taking up most of the strain at these two points. The parts are intended to fit rather snugly so that very little water or foreign matter can enter, but if any water should enter it will flow out through the vent opening 50.

50 By reason of this construction and arrangement the frame 3 may be readily set as illustrated in Fig. 14 and the doors applied later. It will be observed that all exposed parts are flush with the pavement and there are practically no depressions or openings for the drainage of water or for other purposes. This makes a very efficient and tight door structure which will support comparatively heavy weights by reason of its being supported not only around the outer edges but at the center. When the doors are open guard rails may be used, the same being of the usual kind and positioned with the hook ends thereof extending through the respective openings 51 and 52 of the angle iron 53 and the channel iron 10. Preferably 60 there is provided at each end of the channel iron 10 an opening and also a corresponding opening in the angle iron 53 so that there may be a guard iron or rail at each end of the door.

65 In doors of this kind various forms of locks 70 have been provided, and also various forms of handles for opening the doors when necessary. In the present invention an improved combined handle and locking structure is provided which efficiently locks the door and at the same time 75

provides a handle for opening the door when the door is unlocked. This arrangement is shown particularly in Figs. 8 to 12, inclusive. Referring to these figures it will be observed that there is provided a tubular housing 54 having a flange 55 which is secured to the door by suitable screws 56. This housing is open for the full diameter of its bore at the top, and at the bottom is provided with a bottom aperture 57 having an upturned flange 58 fitting into a suitable groove in the core 59 which is rotatably mounted in the housing. This core is provided with a substantially rectangular opening 60, as shown in Fig. 11, said opening extending from the upper end downwardly a certain distance. A plug 61 coacts with the core 59 and is provided with a tubular member or sleeve 62 slidably fitting into the bore 63 of core 59, said sleeve merging into radiating flanges 64 and 65 and an upwardly projecting portion 66 which normally fills the opening 67 in the cover plate 7. The portion 66 is provided with a rectangular depression 68 for receiving a similarly shaped projection 69 on the handle 70. The handle 70 is provided with a rib 71 provided with a stem 72 which merges into laterally extending lugs 73 and 74, said lugs with part of the stem 72 being formed to slide into the opening 60 in the core 59. A substantially rust-proof spring 75 is arranged in the bore 63 and extends upwardly into the sleeve 62 so as to normally hold the various parts in the position shown in Fig. 8, with the flanges 64 and 65 pressing against the under surface of part of the cover plate 7.

When it is desired to operate the lock and open the door, the handle 70 is positioned as shown in Fig. 8 and then moved downwardly until the square member 69 fits into the socket 68. The parts are then forced downwardly until the lugs 73 and 74 have entered the chamber 60, whereupon the grip 71 is rotated for part of a revolution. During this rotation the lugs 73 and 74 will cause the core 59 to rotate a similar distance. This core has a tapering shank 76 which the locking arm 77 is secured to by a bolt or other suitable device, said locking arm being adapted to be swung around to a position beneath the lug 71 or away from that position. When the parts are as shown in Figs. 8 and 9 the locking arm 77 is in locked position, but when it is turned a quarter of a revolution it is in an unlocked position and the lugs 73 and 74 are fitted beneath the overhanging parts of the plate 7, so that the grip 71 may be pulled and the door readily opened. The door cannot be closed until the lock has been moved to locked position and, consequently, when the door is opened the handle 70 is in place. The handle acts at this time as a handle and may be used to swing the door back and forth as often as desired. When the door is swung to closed position the handle is rotated a quarter of a revolution until the locking arm 77 is moved to the position shown in Fig. 9, whereupon the handle may be readily removed as the lugs 73 and 74 are in alignment with the opening 67 of plate 7. (Fig. 10) said opening being substantially of the same size and shape as the opening 60 shown in Fig. 11. After the handle has been removed the door is locked and all the parts are flush with the pavement. By this construction the handle cannot be accidentally left in place to present an obstruction to pedestrians or to any object.

Only one lock has been shown and the same applied to a door 9, but, if desired, the lock could be applied to door 8 at the opposite end without departing from the spirit of the invention.

It will be observed that by reason of the construction presented a very satisfactory door is provided, and all extra gutters and other means for catching water and draining the same have been eliminated. It will also be noted that the door may be manufactured in a very economical manner as all the metal parts except the hinges are fabricated from commercial rolled steel sections and thereby adapt the door to be made for any size opening without the necessity of making individual patterns. Also, the formation of the door in this manner permits repairs to be made at minimum expense in case the door should be damaged at any time. Also, the making of the door of structural steel instead of castings will cause the door to be substantially nonbreakable as well as sturdy and substantial in all its parts. By using the gaskets as specified long life is secured and a substantially noiseless waterproof and air-tight closure is provided, as the weight is not carried by the gaskets but by the properly made supporting bars carried directly by the frame. It is evident that the door may be made of any size and with four hinges, as shown in Fig. 4, or with a larger or less number, without departing from the spirit of the invention.

In forming the frame 3 and the hinges for hingedly mounting the door members, it will be observed that no part of the frame or cover plates are cut away to accommodate the hinges but, on the contrary, the parts are so constructed that the hinges work efficiently though flush when the door members are closed. In addition, the hinge structure is so formed that in case of injury or damage of any kind, access may be readily had to all parts of the hinge without cutting and defacing the material in which the door is set and without injuring any of the parts whatever. In many sidewalk doors the concrete in which the door is embedded must be cut away in order to gain access to the hinges, but in the hinge disclosed in the present invention this is not necessary and, in fact, the parts are so formed that very easy access is had thereto. The hinges and door members are so formed and positioned that they completely cover the steel frame and thereby add a certain amount of safety to all parts.

I claim:

1. A sidewalk door including a frame of structural steel, a plurality of leveling members connected with said frame, a pair of door members hinged to said frame, and means arranged centrally of the frame for supporting the door members along a central line.

2. A sidewalk door including a frame, a pair of door members hinged to said frame and formed of a size to meet along a central line, a lug connected to said frame at each end, and a supporting bar connected to one of said door members and positioned to rest on said lugs, the other door member overlapping said bar when closed whereby when the door members are closed they will be supported on said frame along each edge and by said bar at the center of the frame.

3. In a door of the character described, a frame, a door member adapted to be carried by said frame, and a gasket structure for providing a tight connection between the frame and the door member, said gasket comprising a strip of rubber having a concave upper surface and a grooved lower surface, an apertured plate fitted into said grooved lower surface, the aperture in said plate being threaded, and a screw extending through said door member and the center part of said strip of rubber and into said threaded aperture for

- clamping the strip of rubber against the door member.
4. In a sidewalk door, a frame, a door member associated with the frame, and a hinge for connecting the door member with the frame, said hinge including a socket structure carried by the frame, said socket structure having an abutment, a pintle support carried by the frame and extending into said socket structure, a pintle carried by the pintle support, and a knuckle carried by said door member, said knuckle having a beveled extension projecting into said socket and positioned so that the beveled portion of said extension will strike said abutment when said door member is closed, said knuckle also having an aperture for accommodating said pintle.
5. A device of the character described comprising a hinge having a socket formed with an overhanging abutment, a pair of pintle bars extending to a position for overlapping said socket, said pintle bars each having a pintle receiving aperture, a pintle extending through said pintle bars, a hinge knuckle having a beveled extension projecting into said socket and positioned so that the beveled portion of the extension will strike said abutment when the hinge is fully closed, said knuckle also being arranged between said pintle bars and pivotally mounted on said pintle.
6. In a hinge of the character described, a socket structure having a central arc-shaped depressed portion formed with a thickened portion having an inclined wall, an apertured flange adapted to receive securing means for securing the socket to an object, and a reinforcing web connecting the flange to the remaining part of the socket structure, a pair of pintle blocks, each pintle block being substantially L-shaped with a screw receiving aperture in one arm of the block and a pintle receiving aperture in the other arm, said blocks being spaced apart with the pintle receiving arm extending into said socket and against said inclined wall, a hinge knuckle having an extension fitted between that part of the pair of blocks having the screw receiving apertures, and a head fitting between the remaining part of said pintle blocks, said head having a pintle receiving aperture, an inclined wall adapted to contact with the inclined wall of the socket, and a hook extension, and a pintle extending through said blocks and through said knuckle for swingably mounting the knuckle on said blocks.
7. A door structure, comprising a frame formed of structural metal having a substantially flat top surface, a pair of door members hingedly connected to said frame, a gasket structure connected to said door members and positioned to engage the top surface of said frame when the door members are closed for providing a substantially watertight connection between the door members and the frame, and removably mounted supporting bars connected to said frame and positioned to engage said door members when closed for transmitting the strain from the door members to the frame, said supporting bars being proportioned to cause part of the weight of the door members to be supported by the gasket structure and part by said supporting bars.

JOHN WILLIAM LOVATT.
